US0D1057833S

(12) **United States Design Patent** (10) **Patent No.:** **US D1,057,833 S**
(45) **Date of Patent:** ** *Jan. 14, 2025

(54) **CONTROLLER**

(71) Applicant: **Zwift, Inc.**, Long Beach, CA (US)

(72) Inventors: **Thomas Owen**, London (GB); **Jack Darby**, London (GB); **Natalia Romanova**, London (GB)

(73) Assignee: **Zwift, Inc.**, Long Beach, CA (US)

(*) Notice: This patent is subject to a terminal disclaimer.

(**) Term: **15 Years**

(21) Appl. No.: **29/863,525**

(22) Filed: **Dec. 20, 2022**

(30) **Foreign Application Priority Data**

Jun. 28, 2022 (CN) 202230402497.5

(57) **CLAIM**

The ornamental design of a controller as shown and described.

DESCRIPTION

A portion of the disclosure of this patent document contains material which is subject to copyright protection. This patent document may show and/or describe matter which is or may become trade dress of the owner. The copyright and trade dress owner has no objection to the facsimile reproduction by anyone of the patent disclosure as it appears in the Patent and Trademark Office patent files or records, but otherwise reserves all copyright and trade dress rights whatsoever.

FIG. 1 is an upper perspective view thereof;

FIG. 2 is a front elevational view thereof;

FIG. 3 is a back elevational view thereof;

FIG. 4 is a right side view thereof;

FIG. 5 is a left side view thereof;

FIG. 6 is a top plan view thereof; and,

FIG. 7 is a bottom plan view thereof.

1 Claim, 7 Drawing Sheets
